ATTACHMENT FOR HEADLIGHTS

Frank L. Slezinsky and Irvin F. Elder,
Kingsville, Tex.

Application August 7, 1936, Serial No. 94,856

1 Claim. (Cl. 240—48.6)

This invention relates to an attachment for vehicle and locomotive lamps and the like, and has for one of its objects the production of a simple and efficient shield which may be quickly and easily attached around the base of a light bulb in a manner to support in front of the light bulb an initially circular parabolic shaped reflector having a crescent shaped sector or portion cut out from its lower portion and providing the shield with depending downwardly tapered side portions and an upwardly curved arcuate lower edge between the same, whereby light rays from the lamp bulb and the reflector of a lamp will clearly illuminate a road in front of and at opposite sides of a vehicle but a glaring headlight will be prevented.

A further object of this invention is the production of a simple and efficient shield and means for supporting the same in front of and in spaced relation to a light bulb of a lamp of a reflecting type in such position that the light rays will be prevented from blinding the driver of an approaching vehicle, or a pedestrian.

Other objects and advantages of the present invention will appear throughout the following specification and claim.

In the drawing:

Figure 1 is a vertical sectional view through a lamp casing showing the shield in position upon the lamp bulb;

Figure 2 is a sectional view taken on line 2—2 of Figure 1;

Figure 3 is a perspective view of a lamp bulb, showing the improved shield secured thereto;

Figure 4 is a front elevation of the shield;

Figure 5 is a bottom plan view of the shield applied to a bulb;

Figure 6 is a diagrammatic plan view illustrating the path of the rays of light cast by the lamp utilizing the improved shield;

Figure 7 is a fragmentary front elevation of an automobile showing the headlights provided with improved shield;

Figure 8 is a sectional perspective view of the inner end of the shield holder.

For the purpose of illustration, we have shown a conventional type of automobile lamp within which is mounted the conventional lighting bulb and upon which is secured our improved shield. By referring to the drawing in detail, it will be seen that L designates the lamp which is provided with a conventional reflector R and a conventional lens A. A conventional bulb B is mounted in a conventional manner within the

lamp adjacent the reflector R, and the bulb B is provided with a suitable base C.

Our improved shield comprises a concavo-convex or parabolic shaped reflector 10 which may be formed of any suitable or desired metal, such as tin, aluminum, or chromium, and may if it is desired be highly polished or provided with a reflecting rear or inner face. The lower portion of the reflector 10 has a portion cut therefrom to provide an upwardly curved arcuate lower edge 11 between depending downward tapered side portions 11a of the shield. A plurality of spring arms 12 are secured in any suitable or desired manner to the convex or inner face of the reflector 10, these spring arms being bowed outwardly intermediate their ends and also being drawn inwardly toward each other at their rear ends, the inner or rear ends of the spring arms 12 being secured to an anchoring yoke 13, these arms 12 being secured to the yoke in any suitable or desired manner. The yoke 13 is provided with a pair of spaced arms 14 and 15 at its lower end, the arm 14 having an eye 16 to which is secured a coil spring 17 carrying a hook 18 at its opposite end for fitting over the diverging arm 15 of the yoke whereby the yoke may be tightly held around the base C of the bulb or incandescent bulb B. It will be seen that this structure will greatly facilitate the attaching and supporting of the shade or shield upon the lamp bulb B, and due to the fact that the arm 15 diverges outwardly, the hook 18 of the spring 17 will at all times firmly engage the arm and will not have a tendency to slip off due to the continuous tension of the spring 17, the tension of the spring 17 tending to pull the hook 18 upwardly upon the arm 15.

As is shown clearly in Figures 1, 3 and 5, the shield 10 will be supported in spaced relation to the outer end of the bulb B a sufficient distance to provide a proper reflecting medium and to prevent the direct rays from the lamp bulb from being directed upwardly through the upper portion of the lens A of the lamp L. The cut-away lower portion, however, will allow the rays to be cast with the full intensity of the central portion of the reflector R through the lower portion of the lens A and forwardly along the road directly in front of a vehicle.

Other rays from the central portion of the reflector R will be directed towards sides of the road over a wide lateral area to light up clearly objects on the side of the road and also to allow the driver of the vehicle to easily follow the edge of the road. Still other rays reflected forwardly

by the reflector R outside of what is known as the "bull's-eye" will be directed forwardly for a long distance but as the shield is located in front of the bulb a glaring light will be prevented.

- 5 By referring to Figures 6 and 7 it will be seen that the shield 10 will constitute a crescent-shaped shield disposed in front of the bulb in such position that it will cast a shadow forwardly to prevent a glaring light, but at the same time 10 allow sufficient light rays to pass forwardly under and around it to brightly illuminate the road in front of and at sides of a vehicle. Due to the arrangement of the shield in spaced relation to the front end of the bulb and the fact 15 that the shield is formed with the depending tapered side portions 11^a and an upwardly bowed arcuate lower edge, penetrating light rays will be directed forwardly at no greater height than waist height by the bull's-eye portion of the reflector R and also towards sides of the road while 20 at opposite sides of the forwardly directed bright rays there will be other rays which will effectively illuminate the road but are not blinding as they are outside the bull's-eye area of the reflector. 25 The dark areas shown in Figure 6 between the last mentioned rays and the bright rays directed towards sides of the roads are shadows produced by the tapered side portions of the shield. It will thus be seen that due to its special shape 30 the shield will permit a road to be well lighted in front of and at sides of a vehicle but the shield will cast shadows which will prevent a person from being blinded by a glaring light.
- 35 From the foregoing description, it will be seen that a very simple and efficient device has been produced in the nature of an attachment for lamps, particularly lamps of the headlight type used upon highway motor vehicles, electric and steam locomotives, and the like. The particular 40 structure described and illustrated will project, and control the light produced by the lamp, and the parabolic shaped shield having a lower segmental crescent removed therefrom will provide an efficient means for blocking certain of the up- 45 wardly directed rays and tend to cause these rays to be thrown back upon the main reflector

from which they will rebound and be directed upon the road at points where the light is mostly needed. Furthermore, the certain rays will be thrown at sides of an automobile to increase the field of vision laterally. Furthermore, the present device will serve effectively to apprise 5 pedestrians, drivers of other cars, and other persons upon or near the highway or track, of the approach of the vehicle or locomotive so equipped, and will sharply and clearly define the roadway 10 or right-of-way and any object or obstacle thereon. At the same time the shield will provide means for shielding the rays of light from the eyes of an approaching driver or pedestrian, since these rays will not be reflected directly into 15 the eyes of the person approaching upon or near the highway or right-of-way.

It should be understood that certain detail changes in the construction may be made without departing from the spirit of the invention, 20 so long as such changes fall within the scope of the appended claim.

Having described the invention, what is claimed as new is:

In a headlight, the combination with the light 25 bulb thereof, an anti-glare device comprising a shield having an arcuate lower edge, a resilient yoke adapted to engage the base of the bulb, and having diverging terminals, a spring having one end pivotally connected with one terminal and 30 its other end provided with a hook adapted to detachably and slidably engage the other terminal, a plurality of resilient arms having their forward ends fixed to the shield and their rear ends fixed to the yoke, said arms being disposed 35 in triangular relationship, two of said arms being adapted to engage upon opposite sides of the bulb below the longitudinal axis thereof, and a third arm being adapted to engage the top there- 40 of to hold the shield spaced from the forward end of the bulb and against lateral and vertical displacement whereby the highest point of the arcuate edge will be at all times held below the filament of the bulb.
